INCENDIARY BULLET

Joseph J. Hick, Hays, Pa.

Application April 21, 1942, Serial No. 439,885

2 Claims. (Cl. 102—70)

This invention relates to new and useful improvements in ammunition for machine guns, rifles and other small arms, the principal object being to provide a cartridge for this field of use having an incendiary bullet.

Another important object of the invention is to provide an incendiary bullet which will automatically explode should an attempt be made by the enemy to open the same to detect its construction.

Other objects and advantages of the invention will become apparent to the reader of the following description.

In the drawings—

Figure 1 is a side elevational view.

Figure 2 is a longitudinal sectional view.

Figure 3 is a side elevational view of the bullet proper.

Figure 4 is a cross section on the line 4—4 of Figure 2.

Figure 5 is a longitudinal sectional view through the bullet with its contents removed.

Figure 6 is a side elevational view of the automobile hammer.

Figure 7 is a longitudinal sectional view through the plug of the automatic hammer.

Figure 8 is a sectional view through the retaining washer used in conjunction with the automatic hammer.

Figure 9 is a face elevational view of the washer shown in Figure 8.

Figure 10 is a side elevational view of the hammer element.

Figure 11 is a side elevational view with a part in section showing the firing pin.

Referring to the drawings wherein like numerals designate like parts, it can be seen that numeral 5 denotes a cartridge jacket containing an explosive 6 provided with the usual detonator 7 at the closed end thereof.

Projecting into the other end of the jacket 5 is a bullet 8, the end portion 9 of the jacket 5 being formed into a circumferential groove 10a on said bullet 8.

The bullet 8 is hollow and contains a thermite substance 10. A paper or washer 11 of some other substance is provided in the bullet 8 for holding the thermite in place.

Numerical 12 denotes an elongated firing pin which extends through the thermite containing compartment and has a reduced portion 13 which extends into the nose portion of the bullet and terminates just inwardly of the extremity of the nose portion of the bullet. At the inner end of the pin 12 is a small compartment 14 containing

black powder or like explosive 15 and into the outer end of this chamber 14 is disposed a detonator 16 which is opposed to the pointed head structure 17 of an automatic hammer 18.

5 The automatic hammer 18 is slidably disposed in a bore 19 of a plug 20 which is threadedly disposed into the inner end of the bullet 8 and has openings 21 in its outer end which permits rotation of the plug by a suitable tool or other instrument.

The hammer 18 has a pin extension 22 threaded into a threaded recess 23 in the plug 20, and a spring 24 in the bore 19 tends to urge the hammer 18 with its head 17 toward the detonator 16.

15 In the bullet 8 is a washer 25 having its periphery threadedly disposed in the bullet 8. This washer is at the inner end of the plug 20 and has a squared opening therein for receiving the squared shoulder 26 of the hammer 18.

20 It can now be seen, that when the bullet 8 is discharged from a rifle by the explosive 6, it will eventually strike something which will crumble its nose portion, forcing the firing pin 12 rearwardly until the detonator 16 is set off by engagement with the hammer head 17, thus exploding the charge 15 which passing through the ports 28 sets off the thermite 10, exploding the bullet and setting fire to all nearby inflammables.

Should the bullet 8 not explode when it reaches its objective, and is picked up by an enemy, any attempt to unscrew the plug 20 to inspect the contents of the bullet will result in the bullet exploding.

For instance, should the plug 20 be turned, 35 the washer 25 will remain stationary, and the plug 20 will not only unscrew from the bullet 8 but will screw off of the threaded portion of the hammer pin 22. Obviously, when the plug 20 is freed from the hammer pin 22, the spring 24 will project the hammer toward the detonator 16, exploding the detonator and setting off the powder 15, which, of course, will ignite the thermite 10 and explode the bullet. Thus all evidence of the construction of the bullet will be destroyed.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A bullet comprising a hollow body having an open butt end, a fire-producing explosive sub-

stance confined in said body forwardly of said butt end, and means to explode said substance including a normally fixed, releasable firing pin in said body spring-loaded for projection when released, and a device in the butt end of the bullet to fix said pin, said device being removable from said butt end and releasing the pin when removed.

2. A bullet comprising a hollow body having an open butt end, a fire-producing explosive sub-

stance confined in said body forwardly of said butt end, and means to explode said substance including a detonator, a plug in said rear end and removable therefrom, and a firing pin for projection against said detonator attached to said plug to restrain the same against projection and detachable therefrom under removal of said plug, said pin being spring-loaded for projection against said detonator when detached.

JOSEPH J. HICK.
